United States Patent Office

Des. 197,487
Patented Feb. 11, 1964

197,487

BOTTLE

Arnold I. Lorenzen, Toledo, Ohio, assignor to Owens-Illinois Glass Company, Toledo, Ohio, a corporation of Ohio

Filed Aug. 1, 1963, Ser. No. 76,075

Term of patent 14 years

(Cl. D58—8)

FIG. 1

FIG. 2

The side and back not shown are the same as the side and front shown.

The dominant features of my design reside in the portions shown in full lines.

I claim:

The ornamental design for a bottle, substantially as shown and described.
